UNITED STATES PATENT OFFICE.

DANIEL MCFARLAN MOORE, OF NEWARK, NEW JERSEY, ASSIGNOR TO GENERAL ELECTRIC COMPANY, A CORPORATION OF NEW YORK.

VACUUM-TUBE LIGHTING.

1,037,290.

Specification of Letters Patent.

Patented Sept. 3, 1912.

Application filed April 7, 1906. Serial No. 310,410.

To all whom it may concern:

Be it known that I, DANIEL MCFARLAN MOORE, a citizen of the United States, and a resident of Newark, in the county of Essex and State of New Jersey, with post-office address 52 Lawrence street, have invented certain new and useful Improvements in Vacuum-Tube Lighting, of which the following is a specification.

10 My invention relates to those systems of electric lighting in which the source of light is a luminous gas or vapor contained in a glass tube and excited to luminosity by high potential energy applied through the medium of suitable electrodes at opposite ends respectively of the tube.

My present invention has reference more particularly to that modification of the system in which the tube containing the gas or vapor is distributed or carried over or through the spaces to be illuminated and has its ends located in a danger-proof box wherein the electrodes are connected to the source of high potential energy as described 25 in my prior Patent #702,315. In that system the tube, extended out in any desired direction and to any desired length, is brought back to the protective inclosure wherein the electrodes for both ends of the 30 tube are located. In many instances it is undesirable to dispose a tube in such manner as to form a loop or where the two sides of the loop are close together to form what is in effect a double line of light.

35 The object of my present invention is to avoid the necessity of using the tube in the form of a loop or in such form as to give a double line of light where, under certain conditions, it may be desirable to have but a 40 single line.

A further object is to permit the tube to be extended to a greater distance as a single line than is possible in the system as illustrated in the prior patent.

45 In carrying out my present invention I locate one end of the tube in the proper danger-proof box and within said box I connect the electrode or terminal of that end to the high-potential source of energy or one 50 pole thereof. The tube itself extends from said box and its opposite or distant end is located in another properly sealed box or inclosure, forming a danger-proof box or inclosure, and therein has its electrode or 55 terminal connected to a suitable distribut-

ing wire or conductor leading from an opposite pole of a source of energy. Between said boxes extends an insulating or protective conduit and the said distributing wire or conductor for said opposite end of the 60 tube runs through said conduit for connection to and supplying the electric energy thereto.

Referring to the accompanying drawings, Figure 1 is a general diagrammatic view of 65 an apparatus embodying my invention. Fig. 2 shows a slight modification of the arrangement shown in Fig. 1. Fig. 3 is a further modification embodying my invention.

70 Referring to Fig. 1 of the drawings, 1 indicates a straight or approximately straight length of vacuum tube containing a luminous gas or vapor. The energy transferring electrodes for said tube are indicated at 2, 2' and are located as usual at the ends of the tube and preferably the said ends are enlarged or of greater caliber or cross-section than the main portion which constitutes the light-giving portion.

75 3 indicates a suitable fire-proof and insulating protective box or inclosure which may be of the construction described in my prior patent. In said box or inclosure is located suitable means for supplying the electric 80 energy which renders the contents of the tube 1 luminous. The energy so supplied may be derived from a secondary 4 of a transformer, indicated diagrammatically in the drawings. One terminal of said secondary 4 is directly connected in any suitable manner within the inclosure to the electrode 2.

85 The primary 5 of the transformer takes energy from suitable supply mains 6 or from 90 other source. In this form of my invention the supply wires 6 are low potential supply wires and the transformer is a potential-raising transformer. The high potential supply is, as will be seen, protected and the 100 connection therefrom to the terminal of the tube is made in such protective inclosure.

105 3' indicates a second protective box or inclosure in which the end of the tube 1 having energy transferring electrode 2' is located. The protective case or inclosure 3' may be similar to the inclosure 3 in its structure. It is connected with inclosure 3 by a thoroughly insulated conduit 7 whose ends are coupled securely to the inclosures 3, 3', 110

and through said protective conduit a suitable insulated wire or conductor 8 runs. Said wire 8 is joined at one end directly to the electrode 2' within the casing 3' and its 5 other end is joined to one end of the energy supplying secondary 4 in the protective enclosure or box 3. Said wire and the high potential connections of the electrodes 2 or leading-in wires thereof being all thus se- 10 curedly protected, it is obvious that my system may be safely installed with energy of any desired potential and that the length of tube 1, extending straight away from the enclosure 3 whence the high potential is de- 15 rived, may be anything desired within the limits of the potential used and the conductivity of the gas or vapor within the tube 1.

In the modification of my invention illus- 20 trated in Fig. 2, the wires 6, 6, are them- selves high potential wires led into the inclosure 3 through a suitable conduit or conduits and are of sufficiently high potential to supply directly the energy required for 25 rendering the contents of the tube 1 lumi- nous. No transformer being in this instance employed, the wire contained in the inclosure 7 and running back from the box 3' at the remote end of the tube 1, is joined in the 30 inclosure 3 to one of the wires 6 instead of to a terminal of a transformer secondary. The electrode 2 is directly connected to the other supply wire 6 instead of to a trans- 35 former secondary; otherwise the system is substantially the same as shown in Fig. 1.

Fig. 3 shows my invention as embodied 40 in a system in which provision is made for automatically feeding gas to the tube and in which further, a number of tubes are com- 45 bined in a common system, or are supplied from a common source of energy. In this figure the danger-proof boxes for the ends of the tube are connected by conduit 10, in which is interposed a separate suitable pro- 50 tective inclosure 9 for the transformer of the system, and in which the said trans- former may be located instead of being lo- 55 cated in the protective inclosure for one end of the tube, as shown in Fig. 1.

50 A series of danger-proof boxes 11 for the ends of the tubes, as many in number as there are tubes installed, are provided, as shown, and in said boxes suitable connection is made with the poles of the high-potential 55 source of energy located in this instance in the separate inclosure 9. In this instance, as shown, the conduit is sectional, for con- 60 venience, the sections being joined in the boxes. In this arrangement provision is 65 made for any number of tubes and for locat- ing the transformer in any desired position, but otherwise the system is the same as al- ready described, the only exposed part there- 70 of being the non-conducting portion of the 75 vacuum tubes 1, since electrodes, or leading-

80 in wires, and connections between the same and the poles of the energy supply are all located within the danger-proof boxes and the wire or connection from one or the other pole of the high-potential source is through 70 the conduit running from one box to the other and to which said boxes are secured. At either end of each tube 1 as may be de- 75 sired are also located the means for feeding air or gas into the tube automatically by 75 means of an electromagnet which is con- 80 nected into the circuit of the tube and acts on any increase of the vacuum to open a valve and admit air or gas so as to bring the vacuum back to normal. This I have indi- 80 cated diagrammatically in the case of one box 11 wherein I show the electromagnet 12 in the circuit between the distributing wire in conduit 10 and the leading-in wire of the 85 electrodes 2. Said electromagnet has a mov- 90 able armature or core 13 to which is attached a plunger working in a body of mercury 14 contained in a chamber 15. Said chamber 15 contains a valve which controls admission of air to the tube. Said valve may be con- 90 structed as described in my prior application for patent #275,003, and as indicated com- 95 prises simply a piece 16 of porous material like carbon which is a plug for the end of the feed tube 17 joined to the tube 1. The 95 tip of the plug is slightly exposed above the body of mercury or may be sealed and un- sealed by the changes of level of the body of mercury produced by the plunger or dis- 100 placers.

100 Normally or when the vacuum is at the required tension or degree the tip of the plug is either below the level of the mercury or is but slightly exposed, but on an increase of the vacuum, the magnet acts with greater 105 power and the plunger is raised thus allow- 110 ing the level of the mercury to fall and ex- pose the tip of the plug thus admitting more air. The construction of this valve and the form of the magnet, may obviously be va- 115 ried without departing from my invention.

As will be seen, this system permits the use of a single transformer for supplying any number of tubes distributed or disposed in any desired locations and each provided 115 with its own regulating valve.

What I claim as my invention is:

1. In a system of vacuum tube lighting, the combination of a vacuum tube, a protec- 120 tive inclosure in which one end of said tube is located, a second inclosure in which the opposite end of said tube is located, a conduit to which the said boxes are secured, means for supplying high potential energy to said tube connected as to one of its poles 125 with the electrode of one end of the tube and an insulated wire or connection running from the opposite pole through said conduit to the other box and therein connected to the electrode for the opposite end of the tube. 130

2. In a system of vacuum tube lighting, the combination substantially as described, of a protective conduit having two branches separated from one another and carrying respectively high-potential energy supplying conductors, protective boxes or inclosures inserted at intervals in said branches and vacuum tubes extending from a box inserted in one branch to a box inserted in the other and having their energy transferring electrodes connected in opposite boxes to the supply wires running respectively through the two insulating branches, as and for the purpose described.

15 3. In a system of vacuum tube lighting, the combination substantially as described, of an insulating or protective box or inclosure, a transformer therein, a protective conduit extending in opposite directions

from said inclosure and carrying respectively wires or conductors connected to opposite poles of the transformer secondary, protective cases or inclosures inserted at intervals in said conduit, vacuum tubes having their ends located in boxes belonging respectively to the portions of the conduit containing the conductors for said opposite poles and connections within said boxes between the energy transferring electrodes of the tube and said conductors.

Signed at New York in the county of New York and State of New York this 30th day of March A. D. 1906.

DANIEL MCFARLAN MOORE.
